UNITED STATES PATENT OFFICE

CHARLES G. SMITH, OF MEDFORD, MASSACHUSETTS, ASSIGNOR TO RAYTHEON INC., OF CAMBRIDGE, MASSACHUSETTS, A CORPORATION OF MASSACHUSETTS

ELECTRIC DISCHARGE APPARATUS

Application filed June 13, 1927. Serial No. 198,399.

The present invention relates generally to the art of tube manufacture and in particular to an improved process of making a glass seal and shielding electrodes from ionic bombardment.

Considerable difficulty has heretofore attended fusing of the envelop material about the upstanding conductors notwithstanding the universal employment for sealing-in 10 wires and electrodes, of metal having a coefficient of expansion commensurate with the surrounding glass. Moreover, the materials commonly employed for shielding e. g., lava, are of more or less bulky form and susceptible 15 to fracture.

The difficulties are enhanced in modern apparatus due to the extraordinary increase in power now handled by a single unit causing high temperatures to be localized about the 20 junction of the metal and glass, and in space current apparatus of the gaseous type, there is ever present incessant bombardment by stray ions in the region of the stem. These 25 factors inevitably tend to reduce the life of the device in question.

With these features in mind, I propose to provide a novel form of stem having provisions both for rapidly dissipating the heat gathered about the lower extremities of the 30 electrodes and also for preventing deleterious electrical action taking place at these points. Other objects are to assure an effective seal wherein the actual place of sealing on the sealing-in wire comes in a region where the 35 glass is relatively cool; to improve the manner of supporting the electrodes from the stem and in general, the art of electrical conduction.

The accompanying drawing illustrates a 40 form of tube embodying the new features of the present invention. This embodiment exemplifies an envelop 1 of glass, quartz or the like containing a gas preferably of the mono- 45 atomic group, e. g. helium at a pressure of several mm. Hg, hollow cathode 2 and anodes 3 in rod or pin form, each of refractory material and a base comprising metallic cylinder 4 secured by suitable compound to the envelop in the usual manner. The bottom of 50 the cylinder is closed by insulating disk 5 into

which the ordinary conductor plugs project. The envelop has reentrant stem 6 terminating in press 7, electrodes extending longitudinally of the tube and supported from the press in the manner described hereinafter. The 55 cathode is preferably formed in two parts, the upper comprising a cylinder (or other suitable shape such as conical) closed at one end and the lower part 8 a cover fitting the open end of the cylinder and secured thereto. 60 In the cover there are apertures or openings through which the anodes may actually project or be merely presented to the interior of the cathode. In order to minimize the internal losses of the device I prefer to coat the 65 inner or active portion of the cathode with a substance as alkali or earth alkali to increase the emission or I may polish the surface with a view toward reducing absorption of heat. The cathode is supported at diametral points 70 by two stiff wires anchored to the stem or in any other suitable manner. As shown, concentric with each sealing-in wire 9, in contradistinction to a leading-in conductor, there is a hole or cavity sunk to an appreciable 75 depth and containing an amount of refractory insulating material 10 preferably in granulated or finely divided form, e. g. magnesium oxide. Numeral 11 indicates a metal cylinder or shield individual to each anode 80 preferably of nickel and drawn down to a smaller diameter at its lower part to furnish a snug fit in the outer cavities for sealing.

The upper or flared ends of the upstanding cylinders extend through the apertures in the 85 cathode and are spaced preferably equidistant between the anode and periphery of the opening. The diameters of the apertures, shields and anodes are such that the clearances between juxtaposed surfaces may preferably be of the order of or less than the mean free path of electrons present in the gas, thus providing an insulating short space. Upon connection to suitable circuits, not shown, the device operates upon the ionization principle as a glow discharge, the active region being confined to the enclosed cathode chamber.

From the foregoing it will be evident 90 among the functions of the comminuted 100

insulating material are those of providing long creepage paths between the sealing-in wires and adjacent shields; also of preventing direct contact between the glass and wires at the upper and more heated portion of the press. The lengthening of the creepage paths is beneficial in minimizing deleterious electrical effects taking place at the upper terminating surface of the reentrant stem; moreover, only that portion of the press which is relatively cool actually touches the metal conductors by reason of the glass seal. The shields or cylinders not only discourage ionization at the base of the anodes but also tend to equalize the heat stress throughout the stem by presenting a relatively large contacting surface to the periphery of each cavity to which heat derived from discharge may be readily transferred and distributed. To augment the desirable features of the stem, I may employ copper or other metal of relatively high thermal conductivity for leading-in wire 12 from the connector plugs as far as the envelop, offering additional means of egress for the heat stored in the glass.

While I have described my invention in connection with particular apparatus, it is apparent that its application is quite general and may be employed to advantage with all forms of glow discharge, e. g. amplifiers, oscillators, rectifiers and the like. The invention has also marked utility in the lamp art, the shields being placed about the lower portions of the filament; in case the gas is omitted, the spacing between the anodes, shields and cathode should be changed accordingly.

I claim:

1. A gaseous conduction rectifier having a plurality of electrodes, one of which is a cold cathode, a press of insulating material, conductors sealed therein and extending therethrough, said electrodes connected to said conductors at one end thereof, said press having enlarged openings at the end adjacent the electrodes, each opening surrounding a conductor, a metallic shield embedded in certain of said openings, said shield extending from said openings up to the electrodes and surrounding the conductor and electrode.

2. A gaseous conduction rectifier having a plurality of electrodes including a cold cathode, a glass press, conductors extending therethrough, and sealed therein, said press having enlarged openings at one end surrounding each of said conductors, said electrodes connected to said conductors, and shields for certain of said conductors embedded in the openings and extending to said electrodes, said shields surrounding said conductors and said electrodes and a packing of comminuted material in said enlarged openings.

3. A gaseous conduction rectifier comprising

an envelope containing a rarefied atmosphere, a plurality of electrodes, one of which is a cold cathode, a press therein, conductors extending through said press and sealed therein, said press having enlarged openings around each of said conductors at one end thereof, said electrodes connected to the conductors, certain of said conductors having metallic shields embedded in said enlarged openings and extending along said conductors to said electrodes, said shields surrounding said conductor and electrodes along the entire length of said shield, said shield having a spacing of the order of the mean free path of the atmosphere within said envelope from said electrodes.

4. A gaseous conduction rectifier comprising an evacuated envelope containing a rarefied atmosphere, a plurality of electrodes, one of which is a cold cathode a glass press within said container and having conductors extending therethrough and sealed therein, said electrodes within said envelope connected to said conductors, one of said electrodes substantially enclosing the remaining electrodes, metallic shields around said remaining electrodes, said shields surrounding said remaining electrodes and spaced from adjacent electrodes by a distance comparable to the mean free path of the atmosphere within said envelope, said shields extending from within the enclosing electrode to without it.

5. A gaseous conduction rectifier comprising an evacuated envelope containing a rarefied atmosphere, a plurality of electrodes including a cold cathode a glass press therein, and having conductors extending therethrough and sealed therein, said electrodes connected to said conductors, one electrode substantially surrounding the other electrodes, said other electrodes having metallic shields surrounding them, each of said metallic shields being spaced a distance comparable to the mean free path of the atmosphere within said envelope from adjacent electrodes, each of said shields extending from within said enclosing electrode to without it.

6. An electrical device comprising an evacuated envelope containing a rarefied atmosphere, a glass press therein, conductors extending therethrough and sealed therein, electrodes connected to said conductors, one of said electrodes enclosing the remaining electrodes, each of said remaining electrodes having a shield embedded in the glass press and surrounding the corresponding conductor and electrode, said shields surrounding said conductor and electrodes and being spaced from adjacent electrodes a distance comparable to the mean free path of the atmosphere within said envelope and a finely divided insulating material packed around

each conductor at a portion thereof within the press.

7. An electrical device comprising an evacuated envelope containing a rarefied atmosphere, a glass press therein, conductors extending therethrough and sealed therein, electrodes connected to said conductors, one of said electrodes enclosing the remaining electrodes, each of said remaining electrodes having a shield embedded in the glass press and surrounding the corresponding conductor and electrode, said shields surrounding said conductor and electrodes and being spaced from adjacent electrodes a distance comparable to the mean free path of the atmosphere within said envelope and a finely divided insulating material packed around each conductor surrounded by said shields at a portion of said conductor within the press.

Signed by me at Cambridge, Massachusetts, this 6th day of June, 1927.

CHARLES G. SMITH.
